UNITED STATES PATENT OFFICE

CLIFFORD C. CARSON, OF CHICAGO, ILLINOIS

UNIT HEATER

Application filed November 25, 1929. Serial No. 409,657.

This invention relates to industrial unit heaters of the type used for heating large buildings, auditoriums, theatres or the working areas in large factories and the like. 5 Among other objects, it aims to provide an improved relatively simple, compact and efficient heater having provision for re-circulating and heating room air and for admitting ventilating air to the heater. 10 This application involves certain important improvements on unit heaters of the same general type as those disclosed in my co-pending applications, Ser. No. 308,681 filed Sept. 27, 1928 and Ser. No. 398,443 15 filed Oct. 9, 1929.

In the accompanying drawings:

Fig. 1 is a side elevation of a suspension unit heater embodying the improvements; 20 Fig. 2 is an elevation on a reduced scale showing the arrangement of one unit in a factory building;

Fig. 3 is a longitudinal sectional view of the heater; and

Fig. 4 is a top plan view.

25 In modern shops, factories and large buildings, the conservation of floor space is a great desideratum because of the expense of construction and maintenance. In many instances indirect air heaters are suspended 30 above the floors or mounted on columns, beams and the like so as not to occupy any floor space available for the placement of machinery, etc. But the suspended heaters now in general use are not as efficient as 35 they should be because an unduly large percentage of the hot air delivered by them rises above the working space or the zone to be heated and the heat is lost in the roof zone where it is dissipated by radiation and 40 conduction as well as by cold air currents. This invention, therefore, aims to provide a highly efficient and simple unit heater of this type having provision to insure proper distribution of the heated air in the zone or 45 space to be heated and to confine it to a large extent to that zone.

Referring particularly to the drawings wherein the invention is embodied in a so-called suspension unit heater, there is shown 50 a sheet metal casing 10 having inlet con-

duits or ducts 11 and 12 and a main outlet conduit or discharge duct 13 which is preferably rectangular in cross section. In this example, the casing is substantially T-shaped and the inlet duct 11 is arranged to admit outside air or air from another room, being shown as supported in an opening in a wall of a building 14. The other inlet duct 12 is here shown as extending downwardly to a point above the working area or space to be heated. Conveniently, the duct 12 has a telescoping section 15 so that its height above the floor of the building may be adjusted. As will be seen in Fig. 2, the idea is to recirculate air in the building through the intake duct 12 and also to admit a controlled amount of fresh air from the exterior or from another room, as the case may be. The outlet end of the casing is here shown as being suspended from a ceiling by means of suitable suspension bars or rods 16 although it will be understood that the casing may be supported on columns, beams or the like, depending upon the available supporting structures in a building or large room to be heated.

Within the casing 10 there is shown an air blower 17 which in this instance is an ordinary propeller type fan to which is directly connected an electric motor 18. The arrangement is such that the fan sucks air through the intake ducts and discharges it through the casing into the space to be heated. This fan is suitably mounted within a ring 19 secured to the inside wall of the casing.

Adjacent to the discharge end of the duct 13 and in front of the fan there is shown a heat exchanger conveniently composed of a series of tubes 20 connected at their upper and lower ends to headers 21, the design being substantially the same as those now in common use. However, the upper header 21 is spaced a substantial distance from the upper wall of the casing for a purpose later to be described. Ordinarily, steam or other heat exchanging fluid is circulated through the heat exchanger so as to heat the air blown between the pipes or tubes and discharged from the casing by the fan.

As is usual in some unit heaters, there is shown a plurality of louvres 22 in front of the heat exchanger and they are arranged to be adjusted by means of a suitable rod or 5 bar 23 adapted to be raised and lowered in a guide 24 and clamped in adjusted position, preferably by an ordinary wing nut. The idea of adjusting the louvres is to deflect the heated air at different angles into 10 the space or zone to be heated.

In accordance with the present invention, a part of the air delivered through the casing by the fan or blower element is utilized to create a relatively cold and relatively 15 high velocity stratum or curtain for confining the heated air and causing it to circulate within the working area or space. In my aforesaid co-pending applications, there is disclosed the broad idea of discharging 20 substantially horizontal strata of relatively cold, high velocity air above strata of heated air. In the present instance, it is desirable to be able not only to regulate the thickness and velocity as well as the temperature 25 of the discharging cold air stratum, but also to control the angle at which the stratum is discharged so as to confine the heated air within the desired working range, depending upon the height of the unit above 30 the floor, the width of the building or room in which the unit is located and several other factors. Accordingly, there is shown a pair of adjustable and curved plate members 25 pivoted at their opposite ends and their 35 rear edges between the side walls of the rectangular outlet duct 13 and arranged to be adjusted either independently or in unison. In this example, the shape and arrangement of the plates are such as to provide a substantially 40 Venturi-shaped nozzle in cross section. These plates may be adjusted by various means, but herein there is shown an articulated rod 26 on one side of the casing connected to a pair of pivoted arms 27 and 45 28 having curved slots 29 within which fixed arms 30 on the shafts of the plates are adjustably clamped by means of wing nuts 31 (Fig. 1). The articulated rod is adapted to be clamped in adjusted positions in a 50 suitable clamping guide 32. By the arrangement of the adjusting mechanism, it will be seen that the nozzle may be made to discharge at different angles and the width may be varied in order to vary the thickness 55 of the discharged cold air stratum.

To prevent any of the relatively cold air from escaping below the lower nozzle plate 25 and creating eddy currents, there is shown a fixed baffle member 33 arranged 60 between the upper header 21 and the pivoted rear edge of said plate. Thus, all of the air delivered by the fan must pass through the nozzle and through the heat exchanger.

It is further desirable that the relative 65 volume and, consequently, the relative veloc-

ity and pressure of the cold air stratum shall be regulated in order to assure the maximum efficiency. Obviously, in a wide building, wherein a unit heater of this type is arranged near one side wall as shown, it is desirable that the velocity of the discharging cold air stratum shall be sufficient to prevent it from being deflected downwardly to such an extent as to reach the working zone to be heated. Also, it is contemplated that there are relative critical velocities between the hot and cold air strata which will produce the best results and prevent eddy currents of heated air from commingling with the cold stratum. In this example, there is shown a deflector plate 34 somewhat like an ordinary damper pivoted at its rear edge adjacent to the rear edge of the lower nozzle plate 25. This deflector is adapted to be adjusted by any suitable means but, in this instance, there is shown an arm 35 adapted to be clamped in angularly adjusted positions by means of an ordinary wing nut 36, this being one of the simplest and most convenient forms of adjusting means. When the deflector is lowered a relatively large volume of air is discharged through the nozzle at a higher pressure and velocity. Consequently, the volume and velocity of air passing through the heat exchanger will be diminished.

To enable the stratum of cold air to be deflected, at different angles after it is discharged from the cold air nozzle, there is shown a pivoted baffle member 37 above the discharge end of the duct 13. In this example, the pivoted edge of the baffle has an integral slotted arm 38 adapted to be held in angularly adjusted position by means of a wing nut 39 in much the same fashion as the deflector plate 34. By utilizing this baffle to deflect the discharging stratum of cold air, the angle of discharge can be varied to a greater extent than is possible by adjusting the two nozzle plates 25, because of the limited range of adjustment of said plates. It is desirable, in many instances, that the two strata of air be discharged at a slight angle to each other and when the louvres for the hot air are adjusted, it is a relatively simple matter to change the adjustment of the baffle 37 accordingly without disturbing the nozzle plates.

The relative quantities of fresh air and recirculating air admitted through the intake ducts 11 and 12 are adapted to be controlled by ordinary dampers 40 and 41 connected and arranged to be operated in unison so as to admit a definite quantity of air for all adjustment. In this example, both dampers have operating arms 42 at one side of the casing connected to an articulated adjusting bar 43 adapted to be clamped in different adjusted positions by means of a suitable clamping guide 44.

As is common practice in connection with the well known types of unit heaters, the fresh or cold air admitted through the duct 11 is adapted to be tempered or heated by means of a pre-heater element 45. In this combination, the air pre-heater is utilized in conjunction with the adjustable deflector plate 34 so as to maintain a practically constant temperature differential between the cold air stratum and the heated air when there are variations in the temperature of ventilating air admitted through the cold air intake duct.

In the operation of the heater, it will be seen that the heated air, which always had a tendency to rise to the roof of the building, is confined very largely to circulate below the stratum or curtain of cold air, while the stratum of cold air, which tends to fall to the floor, counteracts to some extent the tendency to rise. The curtain of cold air which travels at a higher velocity than the heated air, is practically impenetrable except by the eddy currents probably set up between the strata. The recirculating intake duct 12 of the heater sucks in the air from above the working area and sets up a continuous circulation of the hot air from the heater downwardly across the building and back into the intake duct so that it does not escape into the upper zone or area of the building and radiate to the exterior.

It is contemplated that very few adjustments of the parts will be necessary or even desirable after the installation is put in operation and the desired or most efficient temperatures, velocities, volumes, thicknesses, directions and relative heights or angles of the strata are established empirically. The temperature of the cold air stratum is regulated to a large extent by the heater element 45; the thickness by means of the nozzle plates 25; the velocity by means of the deflector plate 34; the direction by means of the nozzle plates 25 adjusted in unison and also by the pivoted baffle 37. Moreover, the height of the cold air stratum may be varied with respect to the discharging hot air stratum or stream by means of the nozzle plates 25 independently of the pivoted baffle 37.

While the improvements are shown as being embodied in a suspension unit heater, it is apparent that many of the important features of the invention are equally applicable to floor heaters such as are shown in my aforesaid co-pending applications. Consequently, the claims are not all limited to a suspension type of heater.

Obviously, the present invention is not restricted to the particular embodiment thereof herein shown and described. Moreover, it is not indispensable that all the features of the invention be used conjointly, since they may be employed advantageously in

various combinations and sub-combinations.

What I claim is:—

1. A unit heater of the character described comprising, in combination, a casing having inlet ducts and a discharge duct; a heat exchanger within the discharge duct; a fan connected to discharge air through the casing; louvres arranged in front of the heat exchanger to adjust the angle of discharge of the heated air; and a nozzle arranged above the louvres for delivering a part of the air discharged by said fan above the discharging heated air without permitting such air to be raised in temperature by the heat exchanger.

2. A unit heater of the character described comprising, in combination, a casing having inlet and outlet openings; a fan within the casing; a heating element in front of the fan; means for varying the direction of discharge of heated air therefrom; means for discharging a portion of the air delivered by the fan in a relatively high velocity stratum above the heated air; and means for suspending said heater above the floor of the room or space to be heated.

3. A unit heater having provision for heating and ventilating a working space within a building comprising, in combination, a casing having an air discharge opening; a fan within the casing; a heating element within the casing adjacent to the discharge opening; an adjustable nozzle above said heating element arranged to by-pass a portion of the air delivered by said fan around the heater and create a cold air stratum above the discharging heated air; an intake duct extending downwardly from the casing on the intake side of the fan and arranged to draw air from the space to be heated so as to be re-circulated through the heater.

4. A unit heater of the character described comprising, in combination, a casing having a discharge outlet opening; a fan within the casing; a heating element arranged in front of the fan; means for bypassing a portion of the air from the fan around the heater element whereby to create a stratum of relatively cold air above the discharging heated air; an intake duct connected to the casing at the intake side of the fan and extending through a wall of the room in which the heater is located whereby to draw ventilating air into the room through the heater.

5. A unit heater of the character described comprising, in combination, a casing having an air inlet conduit and a substantially horizontal outlet conduit; heat exchanging means within the casing; a nozzle in the outlet end of the casing to discharge a portion of the air in a thin stratum above the heated air discharged from the heater without passing said air through the heat

exchanger; and means for adjusting the nozzle to regulate the thickness of the cold air stratum.

6. A unit heater of the character described comprising, in combination, a casing; a heat transfer element within the casing having an air discharging duct; a fan connected to deliver air to said heat transfer element and discharge it into the room to be heated; means to discharge a portion of the air delivered by said fan above the heat transfer element without raising its temperature whereby to create a cold air stratum above the discharging hot air; an intake duct for admitting outside air to the casing; an adjustable intake duct for re-circulating the room air through the heater and extending below the level thereof; and means for regulating the proportion of air delivered to the casing by each of said ducts.

7. A unit heater of the character described comprising, in combination, a casing having a pair of intake conduits and a discharge conduit; a heater element within the casing; a fan arranged to draw air from said intake ducts and discharge it through said heater element; means for discharging a stratum of relatively cold air above said heater element so as to confine the heated air to the working space in the room to be heated; means for regulating the quantity and velocity of the air in said cold air stratum; and means to control the admission of air through said intake ducts, one of said ducts being connected to deliver fresh air to the heater and the other extending downwardly below the heater casing to re-circulate room air through the heater.

8. In a unit heater and ventilator of the character described, a casing having air inlet and outlet conduits; a fan within the casing; a heating element in front of the fan; means for controlling the discharging heated air from the heating element into a room to be heated; means for discharging a portion of the air delivered by the fan in a stratum above the heated air; and means for regulating the cold air strata so as to control the temperature, thickness, velocity, direction and height of said strata.

9. A unit heater and ventilator of the character described, comprising, in combination, a sheet metal casing presenting top, bottom and side walls and having an air outlet conduit; a propeller fan in said casing; a heat transferring element in the front portion of the casing; said heat transferring element leaving a free opening above it so as to permit air to flow in a stratum through the opening without being heated and at a velocity slightly higher than the heated air issuing from the heater element; a series of adjustable louvres to direct the heated air issuing from said heater element; a duct connecting said casing with an outside source

of air; a duct extending downwardly from the casing so as to re-circulate the air within the space to be heated through the heater; means for regulating the proportion of air admitted through each of the ducts to the fan; and means for suspending the heater casing above the floor of the space or room to be heated.

10. A suspension heater of the character described comprising, in combination, a casing suspended above the area to be heated and having inlet and outlet openings; a fan within the casing; a heater element adjacent to the outlet opening of the casing; means to deflect the heated air downwardly at an angle from the outlet opening; a pair of pivoted nozzle plates arranged in the upper portion of the outlet opening above the heater element to discharge a relatively thin stratum of cold air at a relatively high velocity above the heated air stratum; means to adjust the nozzle plates so as to vary the thickness of the cold air stratum; means to vary the angle of discharge of the cold air stratum from said nozzles; and means to regulate the relative volumes, temperatures and velocities of the discharging stratum.

11. In a unit heater of the character described, a casing adapted to be suspended above a working area to be heated and having inlet and discharge ducts; a fan within the casing; a heater element in front of the fan adjacent to the discharging end of the outlet duct; a pair of nozzle plates extending across the outlet duct above the heater element and pivoted at their rear edges between the opposite sides thereof; means for adjusting the nozzle plates toward and away from each other whereby to vary the thickness of a stratum of air issuing therethrough; means for varying the angle of discharge from the nozzle including mechanism for adjusting the plates in unison; and a pivoted deflector plate behind said nozzle to regulate the quantity, pressure and velocity of the air issuing from said nozzle.

12. In a suspension unit heater of the character described, a casing having an inlet duct and an outlet duct; a fan within the casing; a heater element arranged in front of the fan adjacent to the outlet duct; adjustable louvres for discharging the air downwardly at an angle from the outlet end of the casing; a pair of pivoted and adjustable nozzle plates arranged above the heater element so as to by-pass and discharge a relatively cold stratum of air above the heated air to confine it within the space to be heated; an adjustable deflector plate behind the nozzle to vary the volume, pressure and velocity of the air discharged through said nozzle; means to vary the angle of discharge of the nozzle; means to regulate the thickness of said cold air stratum; and a pivoted baffle arranged in front of the nozzle

120

125

130

to vary the angle of discharge of the issuing stratum.

13. In a unit heater of the character described, a casing having inlet and outlet openings; a fan connected to discharge air through the outlet opening; a heater within the casing through which a portion of the air passes; an adjustable nozzle within the casing arranged to discharge a relatively thin stratum of relatively cold air above the issuing stream of heated air to confine it to the area to be heated; and means to deflect the issuing stratum of relatively cold air so as to vary the angle of discharge with respect to the stream of heated air.

14. A suspension unit heater having means to discharge heated air downwardly at an angle into the space to be heated; and an angularly adjustable nozzle associated with the heater and arranged to discharge a wide thin stratum of relatively cold air above the stream of heated air to confine it to said space.

15. A suspension heater of the character described comprising, in combination, a casing having a substantially horizontal air outlet duct; an air inlet duct associated with the casing; a heat exchanger including a plurality of vertically disposed tubular elements arranged in said air outlet duct; a fan within the casing behind said heat exchanger; an adjustable nozzle within the outlet duct above the heat exchanger arranged to discharge a thin, relatively wide stream of air delivered by the fan; and means to direct the heated air and the stream of air from said nozzle at different angles of inclination with respect to the horizontal and with respect to each other.

40 In testimony that I claim the foregoing as my own, I have hereto affixed my signature.

CLIFFORD C. CARSON.
